UNITED STATES PATENT OFFICE.

THOMAS G. McMAHON, OF WINNETKA, ILLINOIS, ASSIGNOR OF ONE-HALF TO GUSTAV E. FRITZ, OF CHICAGO, ILLINOIS.

ARTIFICIAL TOOTH.

1,128,703.

Specification of Letters Patent. Patented Feb. 16, 1915.

Application filed August 31, 1914. Serial No. 859,286.

To all whom it may concern:

Be it known that I, THOMAS G. McMAHON, citizen of the United States, residing at Winnetka, in the county of Cook and State of Illinois, have invented certain new and useful Improvements in Artificial Teeth, of which the following is a specification.

This invention has reference to improvements in artificial teeth and relates more particularly to porcelain long-pin-teeth, known as facings, with metal pins baked therein.

In the drawings: Figure 1 is an enlarged sectional view of a tooth showing my improved pin; Fig. 2 is a transverse sectional view of the tooth showing position of pins; Fig. 3 is an enlarged detail view of a pin; and Figs. 4 to 8 both inclusive, show enlarged modifications of the pin.

Like characters of reference denote corresponding parts throughout the figures.

The object of the present invention is to provide a pin for a tooth which will present better longitudinal resistance under stress of mastication on which the backing will slide more easily into position, and by the use of which the cost of manufacture is considerably reduced.

1 designates a suitable tooth and 2 the pins. These pins 2 are of flat metal or ribbon shape and made preferably of metal thirty-four or thirty-six gage. That portion of the pins which are baked in the teeth have roughened, notched, or saw-edges 3 to facilitate in holding the same firmly therein. The protruding portions of the pins are approximately arrow-head shaped or pointed, as at 4 with slightly rounded corners, as at 5. The pointed ends and rounded corners enable the backings to be easily pierced and they may be very easily slid into position on the teeth. The greatest width of the pins 2 extends longitudinally of the teeth, as shown and therefore, will better resist longitudinal stress during mastication.

It has been the custom and practice to use two round pins for the purpose of anchorage or attachment in the porcelain or artificial porcelain facings, but as 95% of all artificial baked in pin facings manufactured are longer than they are wide, I claim that the longitudinal arrangement of pins affords greater strength, because the stress comes against the incisal edge of the facings.

The pin 6 in Fig. 4 has its protruding edges roughened or saw edged, as at 7, serviceable for rubber attachment.

In Fig. 5 the pin 8 has a wedge shaped portion 9 which is baked in the tooth, thus doing away with the roughened or saw tooth edges.

In Fig. 6, the pin 10 has the portion 11 which is baked in the tooth perforated, as at 12. The porcelain will enter these perforations to retain the pin, thus doing away with the roughened edges or wedge shape in the tooth.

In Fig. 7 the pin 13 has its entire body perforated, as at 14, while the pin 15 shown in Fig. 8 has reversal wedge shaped portions as at 16 and 17.

Figs. 3, 5 and 6 are suitable for crown or bridge work and Figs. 4, 7 and 8 are suitable for rubber work.

Although the pins may be modified in construction to provide for securing same in the teeth and to adapt same for crown or bridge work or rubber work, they each and all have the same efficiency so far as resisting longitudinal strain during mastication.

With the use of round metal pins in facings of the character herein, in a great many cases, when the pins are bent over, after the backing has been placed in position, they being stiff and firm, will fracture or crack the porcelain. By using flat ribbon-like pins of very thin gage, this danger is entirely obviated for the reason, that the pins are very pliable and may be bent laterally without danger of fracturing or cracking the porcelain, and yet there is sufficient body to insure a firm and permanent connection between facing and backing.

What I claim is:

1. In combination, a porcelain facing, pins adapted to be used for attaching the facing to a suitable backing, said pins being baked in the facing with portions protruding from the posterior surface thereof, each pin being flat or ribbon-like in cross-section, with the greatest width of the pins extending longitudinally of the facing; the edges of that portion of the pins baked in the facing being notched to insure the pins being held firmly in the porcelain, and the protruding portions of the pins being pointed with slightly rounded corners, to adapt the easy passage of a backing over said pins.

2. As a new article of manufacture, an

anchor for an artificial tooth facing, comprising a very thin bi-laterally symmetrical metallic plate having anchoring means on the part of said plate to be inclosed in the facing, and penetrating means on the other end of said plate.

3. As a new article of manufacture, an anchor for an artificial tooth, comprising a very thin rigid metallic plate having a substantially rectangular body portion, one end of said body portion being pointed to pro-

vide a penetrating member, the other end of said body portion comprising an anchoring member adapted to be secured in the vertical plane of an artificial tooth.

15

In testimony whereof I affix my signature in presence of two witnesses.

THOMAS G. McMAHON.
